To all whom it may concern:

Be it known that I, Thomas F. Figure 1 is a side elevational view of a fountain pen showing my new design;

Fig. 2 is a side elevation as seen from the right of Figure 1; and

Fig. 3 is an end or plan view of the form of Figs. 1 and 2.

The essential features of my design reside in the color contrast of the sections of the fountain pen cap in combination with the configuration, all as illustrated.

I claim:
